Application July 11, 1934, Serial No. 734,646

2 Claims. (Cl. 88—82)

This application is a continuation in part of our copending application Serial No. 644,802, filed November 29, 1932. (Patent No. 2,073,300) which in turn is a continuation in part of our application Serial No. 635,034, filed September 27, 1932.

The present invention relates to a catadioptric unit of the type known in the trade as a reflector button. The general objects of the invention are fully stated in the parent application and the present application relates to that specific embodiment of the invention which is generically claimed in the parent application; in which one of the surfaces is rendered light diffusing by hazard deviations from a true surface, to introduce diffusion to a controlled extent, sufficient only to accomplish the results desired, as fully explained in the parent application.

By our invention as fully explained in the parent application, we provide a simple expedient coincidentally to obtain the following and other desired results, namely, an absence of objectionable chromatic effect, just the desired amount of concentration of the emergent beam for axially incident light and for various angles of obliqueness, and an oblique beam of substantially circular shape in cross section.

For the purpose of this specification "axially" incident light shall mean that the light falling on the reflecting unit is coming from a source located substantially on the axis of the unit and light reflected "axially" or "along the axis" shall mean that the reflected light, or cone of light, is substantially centered on the axis of the unit.

In brief, in accordance with our invention, the complete or partial correction of a simple lens for spherical aberration by any of the several well known methods is impaired so as to afford the desired spread of the axially reflected beam and in combination with the unavoidable oblique aberrations, coma and astigmatism, inherent in all lenses of the corrected type, to produce a beam of more regular shape in cross section and with a controlled amount of divergence, which divergence increases coincidentally with the increasing angle of obliqueness. This impairment is accomplished by an expedient which results in integration of the chromatically separated light and, therefore, in an absence of the chromatic effect. This expedient may conveniently be the providing of the reflecting surface with a relatively minute intermittent deviation from the theoretically correct contour of the surface. For example, the surface may be provided with hap-

hazard minute indentations in the nature of an orange peel effect.

We have found that roughening of the surface of the lens molding tool with a certain grade of emery powder to produce the orange peel effect upon the lens will produce a lens in which the roughened surface will tend to reunite the various colors into white light. This treatment of the mold imparts to the surface of the lens a degree of relatively minute intermittent deviation from the theoretically correct contour of the lens. The mold may be treated in various ways and the precise manner in which it is done forms no part of the invention herein claimed. Alternatively, the hob used for forming the mold may be provided with the desired roughness. This hob is then used to sink the mold and the lenses molded therein will have the particular shape of the surface produced on the hob.

It will be obvious that these minute irregularities or optical inaccuracies in the surface of the lens form a member of exceedingly small refracting surfaces which serve to mix or diffuse the chromatically separated light emerging from the lens.

The function of the irregular surface or surfaces is to introduce a specific amount of controlled diffusion, which acts to mix or reunite the various wave lengths of the light separated by the chromatic aberration of the lens, and also to impair the sharpness of the focus and hence provide the desired increase in spread of the emergent beam centered on the axis and to control and modify the character of the beam obliquely in the respects above referred to.

Other details and advantages of our invention will appear from the following description when read in connection with the accompanying drawing and its scope will be pointed out in the appended claims.

Fig. 1 is a central axial section of an embodiment of our invention having a double convex lens the rear surface of which is reflective.

Fig. 2 is a similar view of a unit in which the reflector is separated from the lens.

The reflector buttons illustrated in the drawing and described below comprise a reflector positioned approximately in the focal plane of a collecting lens whereby a distant source of light is imaged on the reflector and the light is reflected back toward the source as is well known.

The unit shown in Fig. 1 consists of a single unitary lens 50, the rear surface 51 of which is spherical and backed with a reflecting layer 52 of

silver, which in turn may be backed by a protective and supporting layer 53 of copper or other metal. The front surface 54 is convex and aspherical in form and so designed as to correct the lens for spherical aberration as is well known. In accordance with our invention the refracting surface 54 or the reflecting surface 51 is haphazardly roughened a slight amount so that the cones of differently colored light which would normally be formed by the chromatically uncorrected lens will be diffused and mixed to such an extent as to be indistinguishable and the reflected light will appear substantially white to an observer irrespective of his location so long as he is within the field of divergence of the returned light.

One way in which the roughening may be applied to the surface and particularly to the rear surface 51 of a lens such as in Fig. 1, where it is curved and constitutes the reflecting surface, is to form first a spherical mold, then roughen this with an emery powder which will form in the mold roughnesses greater than are finally desirable in the lens surface. When this mold is used with buttons of heated and softened, but not molten, glass, the softened glass does not entirely fill the interstices between the rough particles of the mold but forms minute lenticular convexities in the surface of the glass. The resulting diffusing surface is one which can be reproduced and is distinctly different from the inaccurate surfaces obtained heretofore by pot molding due to slumping and the like. The slumping inaccuracies were not only unpredictable and non-reproducible but generally differed greatly in different lenses. By using molds provided with the desired roughness and the so-called cane molding process, an accurately reproducible diffusing surface is obtained. When this is silvered, it forms a reticulated reflecting surface introducing the desired diffusion. The size of the depressions in the reflecting surface should not be greater than the size of the image of a distant light source falling thereon.

In Fig. 2, the reflector 60 is shown as separated

from the rear surface 61 of the lens 62 and in this case any one of the surfaces may have a haphazard roughening. The lens has an aspherical front surface 64. In general the reflector would have a shorter radius of curvature than the surface 61.

The theory of the effect produced is sufficiently explained in the parent application. The present embodiments are included in the scope of the parent application but the invention herein claimed is limited to the specific embodiments in which the limited amount of diffusion or scattering of the rays, sufficient to smother the effect of chromatic aberration but insufficient to increase substantially the angle of the reflected beam of light, is of a haphazard and not of a systematic nature.

Having thus described our invention, what we claim as new and desire to be secured by Letters Patent is:

1. An autocollimating catadioptric unit comprising the combination of a collecting lens substantially corrected for spherical aberration and uncorrected for chromatic aberration and a reflector behind the lens, at least one optical surface of the unit being accurately reproducible and differing from a single optical surface by relatively minute haphazard deviations of such a size and distribution that chromatic aberration is rendered imperceptible without substantially influencing the correction for spherical aberration.

2. An autocollimating catadioptric unit comprising the combination of a collecting lens substantially corrected for spherical aberration and uncorrected for chromatic aberration and a reflector behind the lens, the rear surface of the lens differing from a single optical surface by relatively minute haphazard deviations of such a size and distribution that chromatic aberration is rendered imperceptible without substantially influencing the correction for spherical aberration.
